(57) CLAIM

The ornamental design for a heel for footwear as shown and described.

DESCRIPTION

FIG. 1 is a right side perspective view of a heel for footwear showing my new design with the opposite left side perspective view being a mirror image;

FIG. 2 is a back perspective view thereof;

FIG. 3 is a right side view thereof;

FIG. 4 is a left side view thereof;

FIG. 5 is a bottom view thereof; and,

FIG. 6 is a back view thereof.

The broken lines in the photographs depict portions of footwear and form no part of the claim.

1 Claim, 6 Drawing Sheets
